UNITED STATES PATENT OFFICE.

ARTHUR R. McARTHUR, OF GARY, INDIANA, ASSIGNOR TO AMERICAN SHEET AND TIN PLATE COMPANY, OF PITTSBURGH, PENNSYLVANIA, A CORPORATION OF NEW JERSEY.

ROLLING-MILL CATCHER.

Application filed June 20, 1927. Serial No. 200,053.

This invention relates to rolling mills of the class used in rolling sheets and plates and more particularly to the provision of novel means whereby the sheets or plates being 5 rolled, either singly or in packs, are mechanically handled or manipulated during the rolling operations, in transferring or returning the sheets or plates from the receiving or "catcher's" side of the mill to the opposite or 10 "roller's" side thereof, into position to be again passed between the rolls for further reduction or rolling.

One object is to provide a mechanical catching mechanism for sheets and the plate rolling 15 mills which will be entirely automatic in operation, which will automatically gage the length of the sheets, and which will deliver the finished sheets in a pile at the rear of the catcher.

Another object is to provide a catching 20 mechanism for sheet and tin plate rolling mechanism which will be composed of few parts, and of comparatively simple construction, therefore reducing its cost of maintenance to a minimum.

In the drawings—

Figure 1 is a sectional plan view of a hot mill having the catching mechanism of this 30 invention applied thereto, the control switches being omitted for clearness.

Figure 2 is a sectional side elevation thereof.

Figure 3 is a sectional elevation on the line III—III of Figure 1.

Figure 4 is a sectional elevation on the line 35 IV—IV of Figure 3.

Figure 5 is a rear end elevation of the catching mechanism.

Figure 6 is a diagram of the electric control 40 mechanism and circuits.

Figure 7 is a fragmentary elevation of the upper portion of the pinch roller housing showing the operating mechanism for the forward control switch.

Referring more particularly to the drawings, the numerals 2 and 3 designate the mill rolls of a sheet or plate hot mill, which are 45 journaled in the usual housing 4.

The catcher of this invention comprises a wheeled frame B composed of top and bottom side beams 5 and 6 tied together and

spaced by suitable vertical and transverse members 7 and 8.

A plurality of bearing blocks 9 are secured to the top of the top beams 5 of the frame and 55 conveyer roller shafts 10 are journaled in the blocks 9. The shafts 10 are adapted to support a plurality of disk like rollers 12, which rollers are spaced on the shafts so as to be staggered with relation to the rollers on the next 60 adjacent shaft and are of such a diameter that the rollers on one shaft overlap the rollers on the next shaft so as to present a substantially continuous conveying surface.

The shafts 10 are each provided with a pair 65 of sprockets 14 and drive chains 15 are trained over the sprockets 14 so as to connect each shaft with its next adjacent shaft. An electric drive motor 16 is mounted on a motor support 17 at the one side of the frame B and 70 has its armature shaft 18 provided with a pinion 19 which is meshed with a gear 20 on a drive shaft 21 journaled in suitable bearings in the frame B. A sprocket 22 is secured on the drive shaft 21 and connected to one of 75 the sprockets 14 on the rearmost conveyer roller shaft 10 by a chain 23.

The motor 16 is adapted to normally drive the conveying roller shafts in a counter-clockwise direction or toward the hot mill, 80 unless reversed by means to be described, so as to normally feed the sheets forwardly over the mill to the "roller's" side thereof.

A pair of pinch roller shafts 24 and 25 are 85 journaled in bearing blocks 26 and 27, respectively, which are mounted in windows 28 in vertical housings 29 at the rear end of the frame B. The shafts 24 and 25 are each provided with roller disks 30 which are opposite each other so as to bite the sheets as they are 90 fed therebetween. The top bearing blocks 27 are adapted to slide vertically in the windows 28 when a sheet enters between the disks 30 and therefore, these blocks are provided with the usual spring mounting, consisting of vertical spring guide rods 31 and springs 32. The rods 31 are adapted to engage and raise a transverse bar 33, when the top roller shaft 25 and blocks 27 are moved upwardly by a sheet entering between the roller disks 30, 95 100 for a purpose to be described.

The lower pinch roller shaft 24 is pro-

vided with a sprocket 34 which is connected by a chain 35 to a sprocket 36 on the rearmost conveyer roller shaft 10.

5 A pinch roller housing 37 is secured to the forward end of the frame B and is provided with windows 38 and 39. Bearing blocks 40 and 41 are mounted in the forward windows 38 and bearing blocks 42 and 43 are mounted in the rear windows 39.

10 Pinch roller shafts 44 carrying pinch rollers 45 are journaled in the bearing blocks 40 and 41 and other pinch roller shafts 46 carrying pinch rollers 47 are journaled in the bearing blocks 42 and 43.

15 The upper bearing blocks 41 and 43 in each of the windows 38 and 39 are each adapted to move vertically in the windows and are provided with the usual spring mounting for normally forcing them downwardly, so as 20 to hold the top pinch rollers against the lower rollers. The spring mounting for the top blocks 41 consists of vertical spring guide rods 49 around which are mounted coiled springs 50 which are engaged between an 25 abutment 51 on the rods 49 and a window cover plate 52 on the housing. The spring mounting for the top blocks 43 consists of vertical spring guide rods 53 around which are mounted coiled springs 54 which are engaged between an 30 abutment 55 on the rods 53 and a transverse plate 56 on the housing. The rods 53 extend through the plate 56 and through upper ends engage a bar 57 so as to move said bar upwardly when the rods 53 are 35 moved upwardly by the entrance of a sheet or plate between the pinch rollers 47.

The lower ones of each of the pairs of pinch rollers 45 and 47 are adapted to be power driven in a clockwise direction and, therefore, 40 the shafts 44 and 46 carrying these rollers are provided with sprockets 58 and 59, respectively, which are connected to a sprocket 60 on a power shaft 61 by a sprocket chain 62 which is trained over the sprockets 58, 59, and 60. The shaft 61 is provided with 45 a gear 63 which is in mesh with a pinion 64 on the armature shaft of an electric motor 65, which motor is mounted on a motor support 66 secured to the main frame B.

50 The top surface of the forward-end one of the conveying rollers 12 on the main frame or table B is materially above the remaining rollers 12, and also materially above the bite of the pinch rollers 45 and 47. It will also be 55 noted that the pinch rollers 45 and 47 are materially above the bite of the hot mill rolls 2 and 3. Therefore, in order to feed the sheets and plates from the hot mill rolls onto the rollers 12, the forward pinch rollers 45 are mounted with their bite materially 60 below the top surface of the rollers 12 and slightly above the bite of the rolls 2 and 3, and the bite of the pinch rollers 47 is arranged slightly above the bite of the pinch

rollers 45 and below the top surface of the 65 rollers 12.

In operation, after the catcher is positioned on the catcher's side of the hot mill, sheets or plates passing from the bite of the mill rolls 2 and 3 will engage the lower pinch 70 roll 45 above its center line and then be forced to enter the bite of the rear pinch rollers 45 which will feed the sheet forwardly into the bite of the other pinch rollers 47, which in turn will feed the sheet upwardly 75 onto the conveying rollers 12 with sufficient force to cause the sheet to coast along the rollers 12 free of pinch rollers 47. The rollers 12 being normally rotated in a counter-clockwise direction or toward the mill will 80 convey or return the sheet forwardly or toward the mill, and, due to the top surface of the upper plane of the forward-end one of the rollers 12 being above the remaining rollers 12 and also above the bite of the pinch 85 rollers 47 the sheet will have its mill or forward end forced upwardly over the forward or mill end conveying roller 12 and over the top ones of the pinch rollers 45 and 47, which rollers are revolved in a counter-clockwise direction to the roller's side of the mill. 90

A small conveying or booster roller 68 is carried by a shaft 68^a journaled in suitable bearings 69 in the pinch roller housing 37 at a point above and forward of the top pinch 95 roller 45, and serves to convey or boost the sheet or plate over the mill. The roller shaft 68^a is provided with a sprocket 70 which is connected by a chain 71 to a sprocket 72 on the upper pinch roller shaft 44. 100

The motors 16 and 65 are adapted to be controlled by standard control drives shown diagrammatically in the drawings.

The motor 16 is adapted to be automatically controlled or reversed by an electrically operated controller 73 which in turn is controlled by switches 74, 75, and 76 operated by the sheets or plates. 105

The switch 74 is mounted in a bracket 77 on the pinch roller housing 37 and is provided with an operating arm 78 adapted to be operated by a rocking lever 79 having a cam end 80. The lever 79 is pivoted intermediate its ends on the bracket 77 and carries a plunger 81 which extends downwardly through the bracket 77 into engagement with the bar 57, which bar is adapted to be raised by the spring guide rods 53 of bearing blocks 43 for the upper pinch roller 47. In operation, the switch 74 is normally open and when a sheet or plate or pack passes between the pinch rollers 47 the top roller will be raised thereby moving the rods 53 upwardly so as to move the bar 57 upwardly and operate the lever 79 so as to operate the switch arm 78 and move the switch 120 into closed position. 125

The switch 76 is similar to the switch 74 and is mounted on a bracket 82 on the pinch

roller housing 29 and is provided with an operating arm 83 adapted to be operated by a rocking lever 84 having a cam end 85. The lever 84 is pivoted intermediate its ends on the bracket 82 and carries a plunger 86 which extends downwardly through the bracket 82 into engagement with the bar 33, which bar is adapted to be raised by the spring guide rods 31, of bearing blocks 27, for the upper 10 pinch roller shaft 25. In operation the switch 76 is normally open, and when a sheet or plate or pack passes between the pinch rollers 30 the top roller will be raised, thereby moving the rods 31 upwardly so as to move 15 the bar 33 upwardly and operate the lever 84 so as to operate the switch arm 83 and move the switch 76 into closed position.

The switch 75 is mounted on a carriage 88 slidably mounted on overhead rails 89 supported above the main frame B by arch-like 20 end members 90. The carriage 88 is adapted to be locked in adjusted position by locking bolts 91, and is provided with an indicator point 92 which co-operates with a scale rod 25 93 to indicate the adjusted position of the carriage.

The switch 75, like the switches 74 and 76, is normally in open position and is provided with an operating arm 94 adapted to be operated to close the switch by a pendulum-like 30 tripping lever 95 pivotally suspended from the carriage 88 and extending downwardly into the path of the sheets or plates. The lever 95 has a head 96 composed of two quadrants of different radii, the rear quadrant being of the greater radius so as to raise the switch arm 94 when the lever is moved rearwardly by the sheets or plates passing thereunder.

40 Now referring specifically to the wiring diagram of Figure 6, the operation and circuits will be described in full.

Assuming that the catcher has been positioned on the catcher's side of the mill, and 45 that the mill is running, the switches 100, 101, and 102 will be closed to connect the several circuits to the lines 103.

When the switch 100 is closed a circuit will be completed to the motor 65 to operate the 50 pinch rollers 45 and 47 as follows—

From one side of the line 103 through the switch 100 to line 104, through the series field 105 of the compound motor 65, and through the armature 106 of the motor 65, to the line 55 107 to the contactors 108 on the automatic starting resistance 108^a. A shunt circuit will also be completed from the line 104 through the shunt field 109 of the motor to line 110, through a manually operated rheostat 111 to lines 112 and 113 to the other side of line 103.

Simultaneously with the closing of the switch 100 a control circuit will be completed from the switch 100 through a line 114, through a manually treadle operated switch 60 115, which is normally closed, and from the

switch 115 through a line 116 to a coil 117 in the automatic starting resistance 108^a. From the coil 117 the circuit is completed through a line 118 to the other side of the main line 103.

The completion of the control circuit through the coil 117 is simultaneous with the closing of the switch 100 and since the completion of the control circuit energizes the coil 117, said coil will operate to move the 70 contactors 108 into closed position successively as is usual in this form of standard starting resistance, so as to complete the circuit through the motor series field and armature from the contactors 108, through the resistance banks 120 to the lines 121 and 113 to the other side of the line. The above circuits will energize the motor 65 and cause it to operate the pinch rollers 45 and 47 and the booster roller 68 and if for any reason the "roller" 80 should desire to stop the pinch rollers and booster roller, he can do so by stepping on the treadle operated switch 115.

Closing of the switch 102 completes the power circuit in the forward direction to the 90 catcher table motor 16 as follows—

From the positive side of line 103 to line 122, to line 123, through a movable contactor 124 of the controller 73 to line 125, then through fixed resistance 126 to line 127 to 95 the armature 128 of the motor 16, through the armature 128 to line 129 and through a fixed resistance 130 and line 131 to a movable contactor 132 of the controller 73. From the contactor 132 the circuit is continued through a line 133 to the series field 134 of the motor 16, through the field 134 to the line 135 and the negative side of the line 103. Simultaneously with the making of the above circuits a shunt circuit is made from the line 105 122 through a line 137, through the shunt field 138 of the motor 16 and shunt line 139 to the line 135 and the negative side of the line 103.

Closing of the switch 101 completes a control circuit for operating the electrically operated controller 73, through a line 140 as far as the switch 74 on the positive line and connects the negative line through a line 141 with the switches 75 and 76. Now, assuming 110 that a sheet is being rolled, it will pass from the rolling mill into the bite of the pinch rollers 45 and 47, successively. As the sheet passes into the bite of the pinch rollers 47 the top pinch roller will be raised as heretofore described and thereby close the normally open switch 74, thereby completing the control circuit from the line 140 through the switch 74 to line 142 and to operating coil 143 of the controller 73. The circuit will 115 continue from the coil 143 through a line 144 to the switches 75 and 76 which, we will assume, are still open. Therefore, the controller 73 will remain in forward closed position and the conveyer rollers 12 on the catcher 120 125 130

table will continue to rotate in a forward or counter-clockwise direction and return the sheet over the top pinch rollers 45 and 47 to the "roller's" side of the mill for re-rolling.

5 After the sheet has been rolled to its required length its rear end will engage the pendulum 95 of the switch 75 while its forward end is still engaged in the bite of the pinch rollers 47, thereby closing both the 10 switches 74 and 75 at the same time. The result of closing both of the switches 74 and 75 at the same time will be to complete the control circuit from the line 144 through the switch 75 and through the line 141 to the 15 negative side of the line 103, thus engaging the coil 143 and causing the controller 73 to move into reverse position. When the controller 73 moves into reverse position, the circuit to the motor armature is reversed as 20 follows—

From the positive side of the line through the lines 122 and 123 to the movable contactor 146 of the controller 73 to connector 147 and through line 131 to resistance 130, line 129, 25 to the motor armature 128. The circuit is continued through the armature 128 and line 127 to resistance 126, thence through line 125, and connector 148 to movable contactor 149 of the controller 73. From the contactor 149 30 the circuit is continued through a connector 150 to the line 133 and through the fields as previously described.

When the motor 16 is reversed by the closing of the switches 74 and 75 the conveying 35 rollers 12 will, of course, be reversed or caused to rotate in a clockwise direction to move the sheets rearwardly along the catcher.

As the sheets are conveyed rearwardly they will move out from between the pinch 40 rollers 47, thereby permitting the switch 74 to open. However, the circuit to the coil 143 remains unbroken due to a shunt from the contactor 146 through a contactor 151 and line 152 to the positive side of the coil 143. 45 In view of the shunt circuit to the coil 143 the controller will be forced to remain in reverse position so as to continue the operation of the motor 16 in reverse direction until the sheet is passed from the catcher.

50 As the sheet is moved along the catcher, the forward end of the sheet will pass from under the pendulum 95 of the switch 75 so as to permit this switch to open. However, prior to the sheet passing from under the pendulum 95 the rear end of the sheet will be engaged in the bite of the rear or feed-out pinch rollers 30 and will have served to move the upper pinch roller shaft 25 upwardly so as to close the switch 76 as previously described. After the switch 76 is closed and the switch 75 is opened the circuit through the coil 143 will remain the same except that the circuit will be through the switch 76 and shunt line 155 from the line 144 to the line 65 141 instead of through the switch 75. There-

fore the controller 73 will remain in reverse position until the sheet has been run completely from between the pinch rollers 30 at which time the switch 76 will automatically open, breaking the circuit to the coil 143 and 70 permitting the controller 73 to automatically return to its forward position to automatically make the forward circuits to the motor 16.

From the above it will be readily understood that the catcher is entirely automatic 75 in operation, may be used to catch various sizes of sheets or plates, and is so arranged that the sheets or plates will be automatically gaged for length.

While I have shown and described one 80 specific embodiment of my invention it will be understood that I do not wish to be limited thereto since various modifications may be made without departing from the scope of my invention as defined in the appended claims. 85

I claim—

1. A hot mill catcher, comprising the combination with a hot mill of a catching table, a plurality of conveying rollers on said table, means for feeding sheets from said mill onto 90 said table, an electric motor for normally operating the conveying rollers in a direction to feed the sheets toward said mill, means for controlling the circuit to said motor for operating said motor in reverse directions so 95 as to operate said conveying rollers in reverse directions and feed the sheets away from said mill, and means including at least one switch operable by said means for feeding the sheets from said mill onto said table 100 for controlling the operation of said circuit controlling means.

2. A hot mill catcher, comprising the combination with a hot mill of a catching table, a plurality of conveying rollers on said table, means for feeding sheets from said mill onto 105 said table, an electric motor for operating said conveying rollers, means for controlling the circuit to said motor for operating said motor in reverse directions so as to operate 110 said conveying rollers in reverse directions, said controlling means being normally positioned to close the forward circuit to said motor so as to cause said motor to operate said rollers in a direction to feed the sheets 115 toward said mill, and interlocked means at opposite ends of said table adapted to be operated in unison by the sheets for controlling the operation of said circuit controlling means to cause said means to close the reverse 120 circuit to said motor so as to cause said motor to operate said rollers in a direction to feed the sheets away from said mill.

3. A hot mill catcher, comprising the combination with a hot mill of a catching table, 125 a plurality of conveying rollers on said table, means for feeding sheets from said mill onto said table, an electric motor for operating said conveying rollers, electrically operated means for controlling the circuit to said mo- 130

tor for operating said motor in reverse directions so as to operate said conveying rollers in reverse directions, and interlocked circuit closing means adapted to be operated in unison by the opposite ends of the sheets for controlling the operation of said motor circuit controlling means.

4. A hot mill catcher, comprising the combination with a hot mill of a catching table, a plurality of conveying rollers on said table, means for feeding sheets from said mill onto said table, an electric motor for operating said conveying rollers, electrically operated means for controlling the circuit to said motor for operating said motor in reverse directions so as to operate said conveying rollers in reverse directions, and interlocked circuit closing means at opposite ends of said table adapted to be operated in unison by the sheets for controlling the operation of said motor circuit controlling means.

5. A hot mill catcher, comprising the combination with a hot mill of a catching table, a plurality of conveying rollers on said table, means for feeding sheets from said mill onto said table, an electric motor for operating said conveying rollers, electrically operated means for controlling the circuit to said motor for operating said motor in reverse directions so as to operate said conveying rollers in reverse directions, a circuit closing means adjacent the mill end of said table, and a second circuit closing means adjustably mounted adjacent the other end of said table and interlocked with said first named circuit closing means, said circuit closing means being adapted to be operated by the sheets being rolled to close the circuit controlling the operation of said electrically operated motor circuit controlling means.

6. A hot mill catcher, comprising the combination with a hot mill of a catching table, a plurality of pinch rollers adapted to feed the rolled sheets onto said table, said table being materially above the bite of said pinch rollers so that plates fed forwardly toward said mill by said table will be conveyed over the top rollers of said pinch rollers to the entering side of said mill, an electric motor for operating said pinch rollers, means operable by the operator for controlling the operation of said motor, a plurality of conveying rollers on said table, an electric motor for normally operating said conveying rollers in a forward direction, means for controlling the circuit to said motor for operating said motor in reverse directions so as to operate said conveying rollers in reverse directions so as to operate said conveying rollers in reverse direc-

tions, and interlocked means operable by the opposite ends of the sheets being rolled for operating said circuit controlling means to cause said means to reverse the operation of said motor and said conveying rollers.

7. A hot mill catcher, comprising the combination with a hot mill of a catching table, a pair of pinch rollers adapted to feed the rolled sheets onto said table, said table being materially above the bite of said pinch rollers so that plates fed forwardly toward said mill by said table will be conveyed over the top roller of said pinch rollers and over the top roll of said hot mill to the entering side thereof, a plurality of conveying rollers on said table, an electric motor for normally operating said conveying rollers in a forward direction, means for controlling the circuit to said motor for operating said motor in reverse directions so as to operate said conveying rollers in reverse directions, and means at the opposite ends of said table operable by the sheets being rolled for operating said motor circuit controlling means, said means being interlocked so as to compel the simultaneous operation of both of said means before said motor is reversed to reverse the operation of said conveying rollers.

8. A hot mill catcher, comprising the combination with a hot mill of a catching table, a pair of pinch rollers adapted to feed the rolled sheets onto said table, said table being materially above the bite of said pinch rollers so that plates fed forwardly toward said mill by said table will be conveyed over the top roller of said pinch rollers and over the top roll of said hot mill to the entering side thereof, an electric motor for operating said pinch rollers, means operable by the operator for controlling the operation of said motor, a plurality of conveying rollers on said table, an electric motor for normally operating said conveying rollers in a forward direction, means for controlling the circuit to said motor for operating said motor in reverse directions so as to operate said conveying rollers in reverse directions, and means at the opposite ends of said table operable by the sheets being rolled for operating said motor circuit controlling means, said means being interlocked so as to compel the simultaneous operation of both of said means before said motor is reversed to reverse the operation of said conveying rollers.

In testimony whereof, I have hereunto signed my name.

ARTHUR R. McARTHUR.
